UNITED STATES PATENT OFFICE.

CHARLES A. MELCHERT, OF KANSAS CITY, MISSOURI, ASSIGNOR TO AUTOMATIC MACHINE MANUFACTURING COMPANY, OF KANSAS CITY, MISSOURI, A CORPORATION OF MISSOURI.

VENDING-MACHINE.

1,152,430.

Specification of Letters Patent.

Patented Sept. 7, 1915.

Application filed November 27, 1914. Serial No. 874,217.

To all whom it may concern:

Be it known that I, CHARLES A. MELCHERT, a citizen of the United States, residing at Kansas City, in the county of Jackson and State of Missouri, have invented certain new and useful Improvements in Vending-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to vending machines, and more particularly to a machine comprising a plurality of individual bins each of which may be unlocked through the intermediary of a coin or check, in order to expose an article contained within that bin for removal by the purchaser; the principal object of the present invention being to provide means for collecting the coins in a common receptacle and for locking the receptacle so that only those possessed of a proper key may have access thereto.

In accomplishing this object I have provided the improved details of structure hereinafter described and illustrated in the accompanying drawings, wherein:—

Figure I is a perspective view of a vending machine constructed according to my invention. Fig. II is a rear perspective with a part of the back plate and part of an end broken away to illustrate the interior construction. Fig. III is a rear perspective of part of one end of the machine. Fig. IV is a vertical section of the machine on a line running through the bin which supports the coin cup, showing the bin open and illustrating the manner of removing the cup. Fig. V is a perspective view of the coin cup and a portion of the lock and supporting bin, a part of the lock being broken away, for better illustration. Fig. VI is a perspective view of one of the bins.

Referring more in detail to the drawings:—The present machine is particularly adapted for hotels, or like places, where the machine may be mounted on the wall of a hall or room, so that guests may purchase articles from the machine without the necessity of leaving their rooms when such ar-

ticles are required, and in order to conveniently mount the machine I provide the same with a stamped metallic back plate 1 which may be nailed or otherwise secured to the wall, and is provided with inwardly stamped ears 2 spaced somewhat from the plate 1, and near the lower edge with a slot 3.

The machine proper comprises a casing 4, which is open at the back to provide access to the interior parts when removed from its mounting, and which is secured to the wall member 1 by upper latches 5 that are secured to the top of the casing and comprise downturned flanges 6 adapted for projection between the ears 2 and the back plate.

Fixed to the bottom of the casing 4 is a U-shaped member 7 having a back leg 9 that extends in the vertical plane of the upper latch flanges 6 and the forward leg 10, which extends to a point above the top of the back leg 9 and is provided with a key opening 11; the back leg having a rearwardly directed lip 12 that is adapted for projection through the slot 3 in the wall member 1 to anchor the parts together.

Pivotedly mounted on a stud 14 on the wall member 1 is a latch 15 having a normally depending leg 16 that is adapted to lie in front of the rear leg 9 of the U-member 8 on the casing, and a front head 17 that is spaced from the leg 16 and is provided with a key socket 18 that normally lies back of the opening 11 in the front leg of the U-member 8 on the casing, so that a key 19, which may be projected through an opening 20 in the front of the casing, may pass through the opening in the U-shaped member into the socket on the latch to turn the latch, so that the leg 16 may be removed from the front of the rear leg of the U-shaped member and thereby release the casing so that it may be swung forwardly and upwardly away from the wall member.

The front of the casing is provided with an opening 22 of substantial size, and located within the casing back of the opening is a housing plate 23, which extends vertically from about the bottom of the opening and thence in an inclined plane to the front of the casing above the opening 22.

Extending longitudinally through the cas-

ing in front of and near the lower edge of the housing plate 23 is a rod 25, and pivotally mounted on said rod 25 are a number of commodity bins 26 of such vertical and horizontal depth that their front faces combine to close the casing opening 22, while their back faces lie flush against the housing plate 23; the rod 25 being extended through apertures 28 in the lower rear corners of the bins, so that unless the bins are supported in some manner they will tilt forwardly (Fig. IV) and expose their open upper ends, so that articles contained within the bins may be removed therefrom.

15 The machine may be provided with any suitable number of bins all but one of which may be adapted for containing a commodity of some character, usually a toilet article, while the remaining bin is adapted for not only containing a vendible article but is also equipped with a coin receptacle and locking mechanism, hereinafter described.

20 In order to support the bins in their upright or closed positions and adapt the same for automatic release upon the insertion of a coin or check, I provide each of the bins with a latch bar 30, which projects rearwardly through a slot 31 in the housing plate 23 and is provided with a hook end 32 that is adapted for engagement by a lever 34 that is pivotally mounted on a pin 35 that projects rearwardly from the back face of the housing plate. A second arm 37 of the lever 34 projects through a slot 38 in the coin chute 39 that is formed by the housing 23 and a cover member 40, one end of the chute opening to a slot 41 in the front of the casing above the particular bin controlled by the latch for that particular coin chute; the arm 37 being yieldingly retained in such position within the chute that it will stop a coin dropping therethrough and the arm 35 being yieldingly tensioned toward engagement with the latch hook 30 by a spring 42 which is connected with a third arm 43 of the lever and fixed in any suitable manner to the chute 39 or other fixed part of the machine. The chute 39 has a slot 44 in the vertical portion of the cap member 40 for receiving an arm 45 that is fixed on a rod 46 which is journaled in bearings 47 that project rearwardly from the housing 23; the said rod being provided with a fixed collar 49 and the said collar being provided with a spring 50, which is connected with the housing to yieldingly retain the arm 40 in upper position, so that a coin may pass through the chute onto the lever arm 37. The ends of the rod 46 project through the ends of the casing and fixed on one end of the rod, exterior to the casing, is a crank 52 which projects through a quadrant 53 and carries a handle 54, whereby the rod may be revolved to move the arm 45 down into contact with

60 the coin to press the same against the lever

and rock the latter to release the bin; the quadrant serving as a stop to limit the downward and upward travel of the crank.

The parts are so arranged that the downward movement of the hand lever will push a coin downwardly into the chute sufficiently to rock the lever 34 to release the bin latch 30 and thereby release the bin so that it may tip forwardly to expose its upper end and permit its contents to be removed.

70 Each of the bins is similarly constructed and located below the open ends of the chutes 39 are inclined troughs 53 having open tops adapted for receiving coins dropped from the lower ends of the chutes, 80 and the inclines being preferably toward the center of the housing, so that the coins from the different chutes may be delivered to a common receptacle.

85 One of the troughs 53 is provided with a chute 57 comprising a forwardly inclined member 58, the lower end of which rests on the edge of a catch box 59 and is provided with a stop lip 60 for retaining the delivery end of the chute on the edge of the catch box. 90 The other trough 53 has its lower end projected into an opening 61 in the body of the chute 57, so that coins deposited in the trough may be delivered into the chute.

95 The catch box 59 is suspended from a lock housing 62, which is removably suspended from the bottom of bin 26' so that when the coins collected by the machine are to be removed the bin 26' may be released and the lock housing disengaged from its 100 mounting in the bin and removed to remove the coin catch box, so that the coins may be removed.

105 The lock housing 62 comprises a metal case having a top, having a depending rear flange 63 provided with openings 64 for receiving the hooks 65 on the upper end of the coin catch box, and having laterally directed flanges 66 which are adapted for overlying the ribs 67 that project inwardly from the 110 opposite sides of said bin to support the lock housing and catch box from the ribs.

115 The housing contains the paired bolt members 68 which are adapted for projection and retraction by a key 69 that may be projected through the key opening 70 in the top of the housing through any ordinary lock mechanism (not shown).

120 The bolts 68 are spaced from the flanges 65 so that when the flanges are supported on the bin ribs, the bolts may be projected beneath the ribs and thereby prevent the lock housing from being withdrawn from the bin while it is supported from the ribs by the flanges 65.

125 The backs of the bins 26 and 26' are preferably provided with upwardly directed lips 72 having hook ends 73 adapted for engagement with a lip 74 that projects rearwardly from the front of the casing 4 at the top of

the opening 22 to limit the outward movement of the bins.

In order to obviate the possibility of an unauthorized person manipulating the latch 5 15 to release the casing from the wall member and thereby gain access to the machine I locate the said latch directly back of the coin catch box, so that it would be impossible for anyone to project a key through the machine until the catch box had been lifted 10 above the plane of the key opening in the front of the case; this arrangement necessitating the removal of the catch box by a person having a key to the catch box lock.

15 In using the machine, presuming the parts to be constructed and assembled as described, and with all of the bins provided with vendible articles, a person wishing to purchase one of the articles drops the proper 20 coin through the slot in the front of the housing over the bin containing the article he desires, and the coin passing down through the chute is stopped by the arm of lever 34, which projects into the chute. The 25 purchaser then operates the crank handle to move the pin 45 onto the coin socket. The coin is pushed against the lever and rocks the lever to release the bin latch and the bin then tilts forward automatically and the 30 article contained therein may be removed. When the coin is pushed past the lever it drops into one of the troughs 53 and travels down the incline into the chute 58 through which it is delivered into the coin catch box 35 that is suspended from one of the bins; the latch lever being moved back automatically by its spring as soon as the coin is past, so that when the bin is refilled and moved back into the machine it will automatically re- 40 lock.

It is apparent that the bins may be operated a number of times without interfering with the collection of the coins as the refilling of the bins and purchase of the articles 45 is entirely independent of the coin collection, so that the bins may be refilled as often as required and coins removed only at infrequent intervals, if desired.

When the coins are to be removed, the collector 50 releases the bin upon which the catch box is mounted, and projects the long handled key through the box into the lock housing to retract the bolts, so that the housing and the catch box which are suspended 55 therefrom may be lifted out of the bin on the end of the key.

When the box is lifted out and the coins removed, it may be replaced by lowering the same into the bin and locked in place by 60 turning the key to shoot the bolts. It is apparent that with this construction it is impossible to remove the coins except through

the bin upon which the box is suspended, and that the box is protected by the lock housing, so that the only way in which the 65 coins can be reached is through the bin. It is also apparent that when the catch box is in place it obstructs the path of the key 19 by which the casing of the machine is locked to the wall member, so that not only 70 is the catch box itself fully protected from pilferers but the safety of the entire machine is insured.

Having thus described my invention, what I claim as new therein and desire to secure 75 by Letters-Patent, is:

1. A vending machine comprising a casing, a plurality of bins mounted in the casing, means for releasing each bin through the intermediacy of a check, a catch box 80 suspended from one of the bins and adapted for removal therethrough, and means for conducting coins through the casing to the catch box.

2. A vending machine comprising a casing, a bin pivotally mounted in the casing, check-controlled mechanism adapted for retaining the bin in locked position, a lock housing removable through the bin and adapted for locking coöperation therewith, 90 a catch box suspended from the housing, and means for conducting coins from the controlling mechanism to the catch box.

3. A vending machine comprising a casing, an open-bottomed bin mounted in the 95 casing, check-controlled mechanism for normally retaining the bin in locked position, ribs on the inner faces of the bin near the lower end thereof, a lock housing having upper flanges adapted for supporting 100 the housing on the ribs, and having bolts adapted to shoot under the ribs to hold the housing in place, a catch box suspended from the housing, and means for conducting checks from the controlling mechanism to 105 the catch box.

4. A vending machine comprising a casing, a plurality of bins mounted in the casing, check-controlled mechanism for retaining the bins in locked position, ribs on the 110 inner faces of one of the bins, a lock housing supported on the ribs and having bolts adapted to shoot beneath the ribs, a catch box suspended from the lock housing, inclined troughs adapted for catching the 115 checks delivered from the controlling mechanism, and means for conducting the checks from the troughs to the catch box.

In testimony whereof I affix my signature in presence of two witnesses.

CHARLES A. MELCHERT.
